OIL WELL PUMP

James R. Hatfield, Bartlesville, Okla., assignor to
 Cities Service Oil Company, Bartlesville, Okla.,
 a corporation of Delaware

Application December 29, 1949, Serial No. 135,678

6 Claims. (Cl. 103—179)

1

This invention relates to oil well pumps and more particularly to a pump permitting the selective pumping of oil from one of two producing zones.

Frequently, an oil well passes through two oil producing zones, having oils of different characteristics. In order to properly control production, conservation laws in the various States require that the producing zones be separated. In addition, conditions of gas-oil ratio, pressure, and water production make it necessary, from an operating standpoint, that they be separated. In general practice this is accomplished by shifting the pump up and down in the well together with the entire tubing string, and necessitating the replacement of the packing which separates the two oil producing zones. This is rather a difficult operation, and cannot be accomplished by the pumper with the tools ordinarily at his disposal.

It is an object of this invention to provide a pump which will permit the pumper to shift from one producing zone to another with a minimum of labor and expense, operating with the tools which are normally at his disposal.

In order that those skilled in the art may further understand my invention and the means for carrying it out, attention is drawn to the accompanying drawings in which

Fig. 1 is a sectional diagram of a string of tubing with sucker rods and a pump in a well showing one form of my invention in which the slide valve is in position for pumping from the lower producing zone,

Fig. 2 is a detailed sectional drawing of the slide valve assembly of Fig. 1 showing the slide valve in position for pumping from the upper zone,

Fig. 3 is a horizontal cross section viewed along line 3—3 of Fig. 2,

Fig. 4 is a sectional drawing of a second form of my invention showing the slide valve in position for pumping from the upper producing zone, and

Fig. 5 illustrates the alternative form of my invention with the slide valve in position for pumping from the lower zone.

As more particularly illustrated in Fig. 1 a string of tubing 10 is inserted in a well having an outside casing 11. Motive power for pumping the well is illustrated in the drawing as a walking beam 12 having attached to the end thereof a horsehead 13. A flexible cable 14 is affixed to the upper end of the horsehead 13 and is removably attached to the upper portion of the sucker rod 15. It will be appreciated, of course, that this type of motive power does not form a part of my

2

invention, and that any other arrangement for raising and lowering the sucker rod may be substituted.

The sucker rod 15 extends downward through a conventional packing (not shown) in the top of tubing 10 to a pump assembly 18, connected to the tubing 10 as by a collar 19, where it is attached to the top valve cage 20 of the pump. The top valve cage 20 contains a conventional ball valve 21 or other form of check valve, whereby the downward flow of oil is prevented throughout the upward stroke of the pump. Attached to the top cage 20 is a plunger 22 which fits closely against a liner 23 enclosed by a reinforcing jacket 24. These latter parts, 23 and 24, perform but a single function, and may accordingly be formed separately, as shown, or as a single unitary structure. The lower portion of the plunger 22 is provided with a lower plunger nut 25 forming a shoulder about the inside periphery of the plunger 22. A garbutt rod 26 provided with an upper flange 27 is positioned within the plunger 22 and is connected at its lower end to a lower valve cage 28 which is also provided with a conventional ball valve 29 or other form of check valve operative to close the flow passage 30 during the downward stroke of the plunger 22.

The bottom cage 28 is connected to a lock hold down mandrel 31 which is provided with inwardly compressible fingers 32 which engage with a lock hold down shoe 33 attached to the jacket 24 having an inner annular shoulder 34 past which the fingers 32 may be forced, whereby to hold the lock hold down mandrel 31 in place.

It will be apparent to those skilled in the art that the foregoing is a description of a standard well pump in which the liner 23, reinforcing jacket 24 and lower valve cage 28 with its connected garbutt rod 26 form the cylinder, while the assembly of the top valve cage 20, the valve 21, and the plunger 22 constitute the piston.

An additional length of tubing 40 is attached to the lock hold down shoe and extends downward in the well for such distance as may be necessary to extend from one producing zone to another, the well being packed with packing 41 of such type and character as to effectively seal one producing zone from the other. The tubing 40 is sealed at the bottom with a plate 42, and is provided with upper zone ports 43 and lower zone ports 44. As illustrated in the drawing, only one row of ports is shown for each producing zone; however, in practice probably several staggered rows of ports will be provided for each zone.

A hollow slide valve 45 is mounted in the tub-

ing section 40 of such diameter that the lower portion thereof fits tightly against the tubing 40 but still not so tightly that it cannot be shifted in position with relative ease. The upper portion of the slide valve 45 is of smaller diameter than the lower portion thereof whereby to provide a shoulder 46 which may fit against stop 47 in the upper portion of the tubing 40, to limit the upward movement of the valve 45, a further stop 48 being provided in the bottom of tubing 40 in order to limit the downward movement of the slide valve 45. The total over-all length of the slide valve 45 is such that when its lower portion is in contact with the stop 48 its upper portion will be in contact with the lock hold down mandrel when the fingers 32 of the mandrel 31 have been pushed past the shoulder 34 of the lock hold down shoe 33. The lower portion of the slide valve 45 is provided with ports 49 so located that they will register with ports 44 of the tubing 40 when the lower portion of the slide valve 45 is in contact with the stop 48. Upper ports 50 are also provided in the slide valve 45 and are so located that they will register with ports 43 of the tubing 40 when the shoulder 46 of the slide valve is in contact with the stop 47. A coil spring 51 is compressibly placed between the bottom plate 42 of the tubing 40 and the bottom portion 52 of the slide valve 45 so as to exert an upward thrust upon the slide valve 45.

Referring to Fig. 1, the pump is shown in position for pumping from the lower zone, with lower tubing ports 44 in register with the lower valve ports 49 and lower valve cage 28 seated in position to act as a standing valve. The piston assembly, consisting of the plunger 22 and the upper valve cage 28 and valve 21, is then reciprocated by the sucker rod 15, actuated by the walking beam 12, and oil is pumped from the lower zone.

In case it is desired to switch production (see Fig. 2) from the lower zone to the upper zone the pumper will disconnect the sucker rod 15 from the cable 14 and will raise, with the tools commonly used to pull the rod string, the sucker rod 15 with attached plunger 22 to a position at which the lower plunger nut 25 will make contact with the flange 27 of the garbutt rod 26. The sucker rod 15 is then raised for an additional distance sufficient to pull the fingers 32 of the mandrel 31 past the shoulder 34 of the shoe 33 so that the mandrel will rest in the position shown in Fig. 2. The coil spring 51 will then force the slide valve 45 into engagement with the stop 47 at which position the upper valve ports 50 will be in register with the upper tubing ports 43, so that oil may flow from the upper producing zone into the flow passage 30. The distance which the mandrel 31 will move in raising it from the position shown in Fig. 1 to that shown in Fig. 2 will usually be 6 inches or more depending upon the design of the mandrel 31 and shoe 33. The operator will then affix the flexible cable 14 to the sucker rod 15 at a point below that at which it was affixed when pumping from the lower zone and at a distance from the point of first fixation equivalent to the distance which the mandrel has been moved. The pump is then in adjustment for pumping from the upper zone and pumping may be commenced.

When operating in shallow wells the force exerted by the resilient fingers 32 against the inner shoulder 34, together with the force exerted by the coil spring 51 is generally sufficient to keep the mandrel 31 in a position above the shoulder 34. However, in fairly deep wells the weight of the liquid column in the tubing may be such that it

is sufficient to force the fingers of the mandrel past the shoulder 34. In such a case an auxiliary standing valve is provided to take over the functions of lower valve cage 28, consisting of a cylindrical housing 53 surrounding the tubing ports 43, attached to the tubing 40 and containing a plurality of conventional ball valves 54. Upon the downward stroke of the plunger 22 the ball valves 54 will be closed and will maintain sufficient pressure in the flow passage 30 to counteract the pressure of the head of oil in the tubing 40, and prevent forcing of the mandrel fingers past the shoulder 34.

If it is desired to shift production back to the lower zone, the pumper will disconnect the sucker rod 15 from the walking beam 12, and lower the sucker rod, together with the top valve cage 20 and plunger 22 until the plunger nut 25 comes in contact with the top of valve cage 28. By placing the weight of the sucker rod string upon the valve cage 28, the resilient fingers 32 of lock hold down mandrel 31 may be easily forced back over the shoulder 34 to hold the mandrel in the position shown in Fig. 1. The lower portion of the fingers 32 pressing against the upper portion of the slide valve 45 will then force the valve down against the stop 48, and bring lower tubing ports 44 and lower valve ports 49 into register. The sucker rod string together with the piston assembly is then raised to pumping position and reattached to the walking beam 12.

It is of note that since the operative parts of my invention are in no way fixed to any of the moving parts of the pump, the pump valves and plunger may be withdrawn from the well for servicing and repair in the usual manner, without interference. Since the tubing and slide valve which embodies my invention is attached to the cylinder of the pump, as by a threaded or welded connection it may be brought to the surface for servicing and repair when the tubing is pulled for inspection of the pump liner 23.

It will be noted that in the form of my invention illustrated in Figs. 1 and 2 the distance between the upper and lower valve ports is less than the distance between the upper and lower tubing ports. In this modification the valve is in position for pumping from the lower zone when its lower portion 52 is in contact with the stop 48, and in position for pumping from the upper zone when the shoulder 46 is in contact with the stop 47. Figures 4 and 5 show a modified form of the invention in which the distance between the upper and lower valve ports is greater than the distance between the upper and lower tubing ports. In this modification the valve is in position for pumping from the upper zone when its lower portion 52 is in contact with the stop 49, and in position for pumping from the lower zone when the shoulder 46 is in contact with the stop 47. Since the fingers 32 of the mandrel 31 rest against the top of the annular shoulder 34 when the valve is in position for pumping from the lower zone, the auxiliary valve housing 53 is positioned to surround the lower tubing ports 44, in order to maintain sufficient pressure in the flow passage 30 to counteract the head of oil in the tubing 40 during the downward stroke of the plunger 22. In this modification the same steps are taken to shift from zone to zone as described above, but the reverse results are obtained. That is, a raising of the sucker rod to pull the fingers 32 of the mandrel 31 past the shoulder 34 of the shoe 33 will shift production from the upper to the

lower zone, whereas forcing the fingers downwardly past the shoulder will shift production from the lower to the upper zone.

It will be apparent to those skilled in the art that the major portion of the pump illustrated in the drawings is a conventional pump of the type known as a tubing liner pump, and that my invention resides in combining with this pump an additional section of tubing extending from one producing zone to another, having ports in each zone, a slide valve movable within the tubing and having ports capable of selectively registering with either the upper or lower tubing ports, and means for selectively positioning the slide valve so that production may be shifted from one zone to the other easily and simply. It is of particular note that in shifting from one producing zone to the other the tubing and pump remain in place, the shift from one zone to the other being accomplished merely by manipulation of the sucker rod string, which the pumper may easily do with the aid of such tools as are ordinarily at his disposal.

Having now described my invention, what is claimed as new and useful is:

1. An oil well pump assembly operative to selectively pump from two producing zones including in combination a hollow plunger operatively connected to a sucker rod string, a liner fitting about the plunger, a jacket enclosing the liner, a plunger nut forming an inner shoulder about the interior circumference of the lower end of the plunger, a garbutt rod extending into the interior of the plunger, a flange attached to the upper end of the garbutt rod adapted to engage with the plunger nut, a mandrel operatively connected to the lower end of the garbutt rod and provided with inwardly compressible fingers adapted to engage an inner shoulder of a lock shoe attached to the lower end of the jacket, a downwardly extending length of tubing attached to the lower end of the lock shoe, the said tubing being closed at its lower end, upper and lower sets of parts in said tubing, a hollow slide valve enclosed within the tubing, upper and lower sets of ports in said valve, a spring compressibly inserted between the closed end of the tubing and the slide valve exerting an upward force upon the slide valve, the said slide valve having an exterior diameter at its upper portion less than the exterior diameter at its lower portion forming a shoulder near the upper portion of the slide valve, a stop near the upper end of the tubing adapted to engage the said slide valve shoulder, and so positioned than when the said stop is in engagement with the said shoulder, one set of valve ports are in register with one set of tubing ports, a stop near the lower end of the tubing adapted to engage the bottom portion of the slide valve, and so positioned that when the said stop is in engagement with the said bottom portion of the valve, the other set of valve ports are in register with the other set of tubing ports.

2. An oil well pump assembly including in combination a rod-operated pump having a lower pump valve cage, a downwardly extending length of tubing attached to the lower end of the pump, the said tubing having a closed bottom and having lower and upper sets of ports, a slide valve contained within the said tubing and movable lengthwise therein, and having upper and lower sets of ports spaced apart at a distance unequal to the distance between the upper and lower tubing ports, the said lower pump valve cage being movable relative to said tubing and oper-

atively connected with said slide valve and in fluid communication therewith, spring means compressibly inserted between the tubing bottom and the slide valve, and a rod string extending to the ground surface and operatively connected with the lower pump valve cage whereby a vertical movement of the rod may be communicated to the said valve cage and its associated slide valve to move the said valve cage and slide valve relative to the tubing to cause the slide valve ports to shift from communication with one set of tubing ports to the other.

3. An oil well pump assembly including in combination a rod-operated pump having a lower pump valve cage, a downwardly extending length of tubing attached to the lower end of the pump, upper and lower sets of ports in the tubing, a slide valve container within the said tubing movable lengthwise therein and having upper and lower sets of ports spaced apart at a distance unequal to the distance between the upper and lower tubing ports, the said lower pump valve cage being movable relative to the said tubing and operatively connected with said slide valve and in fluid communication therewith, a rod string extending to the ground surface and operatively connected with the lower pump valve cage whereby a vertical movement of the rod may be communicated to the said valve cage and its associated slide valve to move the said valve cage and slide valve relative to the tubing to cause the slide valve ports to shift from communication with one set of tubing ports to the other, and a valve housing enclosing the tubing ports which are in communication with the slide valve ports when the slide valve is in upper position, the said valve housing having a check valve therein.

4. An oil well pump assembly including in combination a rod operated pump having an upper valve cage and a lower valve cage, a tubing extension attached to the lower end of the pump, the said lower valve cage being movable longitudinally relative to the said tubing extension, lower and upper ports in the tubing extension, a hollow slide valve contained within the tubing extension and having upper and lower ports spaced apart at a distance unequal to the distance between the upper and lower tubing ports, the lower valve ports being capable of registering with the lower tubing ports, and the upper valve ports being capable of registering with the upper tubing ports, the said slide valve being operatively connected with the said lower valve cage and being in fluid communication therewith.

5. An oil well pump assembly including in combination a rod-operated pump having an upper valve cage and a lower valve cage, a tubing extension attached to the lower end of the pump, the said lower valve cage being movable longitudinally relative to the said tubing extension, lower and upper sets of ports in the tubing extension, a hollow slide valve contained within the said tubing extension, the said slide valve being operably connected with the lower valve cage and in fluid communication therewith, ports in the said slide valve, the said ports being capable of selectively communicating with the upper or lower ports in the tubing extension, and a rod extending to the ground surface and operatively connected with the said lower valve cage whereby a vertical movement of the rod will be communicated to the said lower valve cage and its associated slide valve to move the said valve cage and slide valve relative to the tubing extension where-

by to cause the said slide valve ports to shift from communication with one set of tubing ports to the other.

6. An oil well production assembly including in combination packing means adapted to be set in a well between an upper and a lower producing well stratum so as to separate the well into an upper well zone communicating with said upper stratum and a lower well zone communicating with said lower well stratum, production tubing passing through said packing means, upper and lower sets of ports in said production tubing communicating respectively with said upper and lower zones, a rod-operated pump assembly interposed in the production tubing, the said pump assembly having an upper valve cage and a lower valve cage, the said lower valve cage being movable longitudinally of the production tubing, a hollow slide valve contained within the production tubing below the said lower valve cage, the upper end of said slide valve being operably con-

5 nected with said lower valve cage and in fluid communication therewith, ports in the said slide valve, the said ports being capable of selectively communicating with the upper or lower ports in the production tubing, and a rod extending to the ground surface and operatively connected with the said lower valve cage whereby a vertical movement of the rod will be communicated to the said valve cage and its associated slide valve to move the said valve cage and slide valve relative to the production tubing to cause the slide valve ports to shift from communication with one set of tubing ports to the other.
